UNITED STATES PATENT OFFICE

EARL C. HERVEY, OF INDIANAPOLIS, INDIANA, ASSIGNOR TO HYDRAULIC-PRESS BRICK COMPANY, OF INDIANAPOLIS, INDIANA, A CORPORATION OF MISSOURI

ORNAMENTAL BRICK AND METHOD OF PRODUCING SAME

Application filed December 22, 1930. Serial No. 504,087.

The object of my invention is to produce a brick having a new ornamental effect, such new ornamental effect being the result of a new method of manipulating the raw material from which the bricks are made at a period between the issuance of the raw column from the forming machine and the subjection of the brick to the fire and preferably at a time between the issuance of the clay column from the forming machine and the subjection of such column to transverse cutting to individualize the brick.

The accompanying drawings illustrate my invention.

Fig. 1 is a general perspective view of a brick-forming machine capable of performing my improved method and producing the new brick;

Fig. 2 is a perspective showing portions of the forming mechanism at the point where the novel step of my improved method is performed;

Fig. 3 is a perspective of the same portions of the mechanism shown in Fig. 2, but from another viewpoint, and

Fig. 4 is a perspective of a group of the new brick.

In the drawings 10 indicates the column-forming mechanism, of common form, from which issues a continuous column of clay 11 the cross sectional dimensions of which are equal to two of the dimensions of the desired brick.

Arranged at the mouth of the die across the top of column 11 is a cutting wire 12 so positioned that it will separate a thin layer 13 of clay from the main body of the column, said layer being caused to over-ride the cutting wire and deflected down upon the top surface of the column 11 by a deflector 14. Thus far the mechanism is similar to that disclosed in the patent to Buckley, No. 1,207,272. In the operation of mechanism of this kind the layer 13 breaks up into comparatively narrow sections 15 which, in the main, retain their continuity across the width of the column but are separated lengthwise of the column, these narrow bands or strips being of irregular widths and side outline, although, in a small percentage of the product,

these transverse strips are broken intermediate of their lengths. In the main, however, they are fairly regular and, when reincorporated with the clay column, produce rib-like projections on the face of the brick which are fairly regular in character alignment and spacing.

The column 11 passes to the upper run of an endless belt 16 which transports it to the transverse cutting mechanism 17 of usual character, passing preliminarily beneath a roller 18, covered with sheep-pelt, which has sufficient weight to cause whatever fragments may be lying upon the upper surface of the column to be re-adhered to the column.

In order to produce my new product I break the strips 15 at one or more points intermediate of their lengths into fragments 15' and angularly shift these fragments upon the surface of the column, as clearly illustrated at the right in Fig. 2 and at an intermediate point in Fig. 3, these fragments 15' then passing under the pressure roller 18 and caused to adhere to the column. The column then passes through the transverse cutting mechanism 17, where the column is individualized into bricks and the individual bricks then pass beneath a pressure roller 20, the surface of which is kept moistened with oil so that the top surfaces of the fragments 15 are glossed so that, in the process of burning, they will be glossed as compared with the rough sub-surface 25 of the face of the brick to which the fragments are adhered.

It will be readily understood that the breaking into fragments of the strips 15, and the angular shifting of the same may be accomplished in a number of ways and by a number of different mechanisms. In practice I have found that very satisfactory and artistic results are obtainable by the use of two light wire fingers 26, 26 which, at their upper ends are anchored upon a cross bar 27 beneath which the column passes on its way to the cutting mechanism, and the lower ends of which are bent, as indicated at 26', to produce short downwardly and rearwardly projecting fingers having lengths somewhat greater than the thickness of the strips 15. The cross bar 27 is conveniently angularly

adjustable, about a horizontal axis, so that the free ends of the fingers 26 will project below the plane of the upper surfaces of the strips 15 and will just clear the upper surface of the 5 main body of the column so that these fingers, while serving to impede the passage of the strips 15, will not mar the surface 25 of the column.

With this arrangement, as will be clearly 10 seen in Figs. 2 and 3, the strips 15 are initially substantially coextensive with the width of the column, are broken into fragments, as the column passes beneath the fingers, and these fragments are irregularly shifted angularly 15 upon the face of the column.

As a result of the fragmentation and angular displacement of the pieces 15', and their reincorporation with the main body of the clay, a brick is produced which, when laid in 20 a wall, looks as though it were covered with a thin layer of leaves, as contrasted with the product disclosed in Patent No. 1,207,272 which, in practice, looks much as the bark of a rough-bark tree. The sub-surface of the 25 finished brick, to which the fragments are adhered, will have a surface characteristic varying with the character of the element by means of which the fragment material has been separated from the main body of the 30 column. Where a wire is used for this separation the sub-surface will be rough and the degree of roughness will increase with the diameter of the cutting wire.

I claim as my invention:

35 1. The method of producing a rough-face brick which consists in ejecting a column of suitable material, separating a thin layer of said material from the upper face of the column, breaking said thin layer into comparatively narrow irregular strips, redepositing said strips upon the surface of the column from which the layer was removed, breaking said strips into fragments and angularly displacing said fragments, re-adhering the frag-

40 ments to the face of the column from which they were removed, and subjecting dimensioned portions of said column with its adhered fragments to a burning heat.

45 2. The method of producing a rough-face brick, which consists in ejecting a column of suitable material, separating a thin layer of said material from the upper face of the column, breaking said thin layer into comparatively narrow irregular strips, redepositing said strips upon the surface of the column from which the layer was removed, breaking said strips into fragments and angularly displacing said fragments, re-adhering the frag- 50 ments to the face of the column from which they were removed, subjecting the outer surfaces of said fragments to a treatment which will cause them, in the ultimate product, to have a smoother appearance than the exposed 55 sub-surface of the main body, and subjecting

dimensioned portions of said column with its adhered fragments to a burning heat.

3. The method defined in claim 1 wherein the fragmentation is accomplished along a line parallel with the vertical faces of the 70 column.

4. The method defined in claim 1 wherein the fragmentation and angular displacement of the strips is accomplished along a plurality of lines parallel with the vertical faces of the column by obstructing the flow of strips with the column at intermediate point in the lengths of the strips.

5. As a new article of manufacture, a brick, one face of which is formed by a sub-surface of the main body of the brick and by a multiplicity of irregular chips of the same material of uniform thickness and density adherent to the sub-surface and of lengths less than half the longest dimension of the 80 face to which they are adherent and substantially angularly displaced relative to the cross dimensions of said face.

6. As a new article of manufacture, a brick, one face of which is formed by a sub-surface 90 of the main body of the brick and by a multiplicity of irregular chips of the same material of uniform thickness and density adherent to the sub-surface and of lengths less than the longest dimension of the face to 95 which they are adherent and substantially angularly displaced relative to the cross dimension of said face.

In witness whereof, I have hereunto set my hand at Indianapolis, Indiana, this 18th 100 day of December, A. D. one thousand nine hundred and thirty.

EARL C. HERVEY.
